UNITED STATES PATENT OFFICE.

LLOYD STEARMAN, OF WICHITA, KANSAS.

DESIGN FOR A CABIN AIRPLANE BODY OR SIMILAR ARTICLE.

Application filed April 8, 1929. Serial No. 30,795. Term of patent 14 years.

To all whom it may concern:

Be it known that I, LLOYD STEARMAN, a citizen of the United States, residing at Wichita, county of Sedgwick, and State of Kansas, have invented a new, original, and ornamental Design for a Cabin Airplane Body or Similar Article, of which the following is a specification, reference being had to the accompanying drawings, forming part thereof.

In the drawings, Fig. 1 is a side elevation of a cabin plane showing the new design; Figs. 2 and 3 are front and plan views respectively of the same.

What I claim is:

The ornamental design for a cabin airplane body or similar article, substantially as shown.

LLOYD STEARMAN.
